(57) **CLAIM**

The ornamental design for a twin body fishing lure, as shown and described.

DESCRIPTION

FIG. 1 is a side and top perspective view of a twin body fishing lure showing my new design;

FIG. 2 is a side elevation view of the twin body fishing lure of FIG. 1. The opposing side elevation view is a mirror-image. FIG. 3 is a top view of the twin body fishing lure of FIG. 1. FIG. 4 is a bottom view of the twin body fishing lure of FIG. 1.

FIG. 5 is a front view of the twin body fishing lure of FIG. 1. FIG. 6 is a rear view of the twin body fishing lure of FIG. 1; and,

FIG. 7 is a side and top perspective view of the twin body fishing lure shown in FIG. 1, illustrating another type of tail. The remaining views being the same as those shown in FIGS. 2-6.

The broken lines and contour shading depict portions of the drawing that do not form part of the claim design.
